UNITED STATES PATENT OFFICE.

WILLIAM F. GRADOLPH AND GODFREY MUELLER, OF TOLEDO, OHIO, ASSIGNEES TO THE DE VILBISS MANUFACTURING COMPANY, OF TOLEDO, OHIO, A CORPORATION OF OHIO.

SPRAY GUN.

Application filed August 2, 1924. Serial No. 729,713.

This invention relates to spray guns, and particularly to the control or operating means therefor.

The object of the invention is the provision of a simple and efficient automatic means for controlling and effecting periodic operation of spray guns of the machine operated type, and also has for its object the provision of an automatic control for spray guns, which control is adapted to be substituted for the handles of hand operated spray guns to provide a mounting and operating means for such guns.

The invention is fully described in the following specification, and while in its broader aspect it is capable of embodiment in numerous forms, two only of such embodiments are illustrated in the accompanying drawings, in which—

Figure 1 is a side elevation of a spray gun embodying the invention with parts broken away and with the control means in normal at rest position, and Fig. 2 is a similar elevation of a spray gun with parts broken away and removed and embodying a different form of the invention.

Referring to the drawings, 1 designates the body of a spray gun of a type commonly used, having a rearwardly projecting shank 2 to which a handle or other carrying means may be attached, and having at its forward end a spray-head 3. Nipples 4 and 5 are provided on the body 1 for connection, respectively, with air pressure and paint, or other material, supply tubes, and the passage of air to the spray-head is controlled by a valve having a reciprocally movable stem 6, while the passage to the spray-head of material to be sprayed is controlled by a valve having a reciprocally movable stem 7, as well understood in the art. A spring-pressed plunger 8 is mounted in the shank 2 to bear against the rear end of the stem 7 to hold its valve normally seated, and a spring 9 acts on the air valve to normally maintain it seated. For a more detailed description of a spray gun of this construction, reference is made to our co-pending application Serial No. 682,700, filed December 26, 1923.

A trigger or valve operating member 10

is mounted on a pivot 11 within a portion of the body 1 in advance of the shank 2 and has a finger 12 projecting up in engaging relation to the rear end of the valve stem 6, and a finger 13 projecting down in advance of a shoulder 14 on the stem 7 in engaging relation thereto. The trigger 10 has a third finger 15 projecting rearwardly therefrom and adapted, when swung upward, to cause the finger 12 to have valve opening engagement with the stem 6 and the finger 13 to have valve opening engagement with the stem 7. The construction, so far described, is old, except that the trigger finger 15 in the former construction extended down into position below the body of the gun to be engaged by a finger of the hand of the operator holding the gun.

The instrument is supported in usable position on the machine or apparatus with which associated by a standard 16 provided at one side with an apertured ear 17 to enable it to be clamped to a suitable support (not shown). The standard 16 is provided at the rear edge portion of its upper end with a boss 18 having a horizontally disposed opening therethrough for receiving the shank 2 of the gun body, being held on said shank by a nut 19 threaded on the rear end of the shank.

A chamber 20 is provided in the standard 16 and the standard is made of two separable parts *a* and *b*, which are threaded together, to permit access to said chamber. A solenoid frame 21 carrying an electric coil 22 is mounted in the chamber 20, and a core-post 23 is movably mounted in the frame 21 and coil 22 longitudinally of the standard 16, projecting at its upper end through the upper end of the standard in advance of the boss 18 and shank 2 and being forked or split to straddle the stem 7. When the solenoid is energized by the passage of an electric current through its coil, the core-post 23 moves upward and its upper end strikes the trigger finger 15 and effects a rocking of the finger to move both valve stems 6 and 7 to open positions to effect a discharge of material in spray form from the spray-head 3 of the gun.

The leads for the coil 22 extend from the

chamber 20 through a conduit 24 that is connected to the lower end of the standard 16 with its opening in communication with said chamber.

5 In the form of the invention shown in Fig. 2 the standard which carries the gun is designated 25 and forms a cylindrical chamber 26, the outer end of which is closed by a cap 27 having an air line of fluid pressure connection 28 in communication with the interior of the chamber. A piston or plunger 29 is mounted in the cylinder 26 and has a stem 30 projecting upward therefrom through a registering opening in the 10 upper end of the cylinder and into position to engage the trigger finger 15 and operate the trigger to open both control valves of the gun on an upward fluid actuated stroke of the plunger within the cylinder. The 15 cylinder 25 is provided with a relief vent 31. A coiled expansion spring 32 is interposed between the plunger 29 and upper end of the cylinder in encircling relation to the stem 30, and acts to normally retain the 20 plunger in its lowered position.

It is evident with both forms of the invention that upon an upward movement of the trigger actuating member, whether such member constitutes an electrically operated 30 core member 23, a fluid actuated stem 30 or some other automatically actuated part, the finger 15 of the trigger is engaged thereby and a rocking of the trigger effected so as to cause the finger 12 to engage the valve 35 stem 6 and the finger 13 to engage the shoulder 14 of the valve stem 7 and impart valve opening movements to such stems. As soon as the force which actuates the trigger 40 operating movement of the control member has been removed, such member will return to its normal inoperative position, permitting a closing of the air and liquid control 45 valves of the gun.

We wish it understood that our invention 50 is not limited to any specific construction, arrangement or form of the parts as it is capable of numerous modifications and changes without departing from the spirit of the claims.

55 Having thus described our invention, what we claim as new and desire to secure by Letters Patent is:

1. A spray gun having air and liquid control valve stems, a trigger operable to engage both stems to impart opening movements to the respective valves, a movable member operable to engage the trigger and impart valve opening movements thereto, and means operable to impart trigger actuating movements to the member.

2. A spray gun having an air valve stem and a liquid valve stem, a trigger having separate fingers acting on said stems to impart opening movements thereto in reverse

directions when the trigger is rocked in one direction, and means having a member movable transverse to the trigger axis and operable to engage and actuate the trigger to impart valve opening movements to said stems.

3. A spray gun having a body, control-valve stems movably carried by said body, a trigger pivoted to the body and operable, when rocked in one direction, to engage and impart valve opening movements to said stems, a standard supporting the body and having a chamber therein, and means mounted in the chamber and having a member projecting therefrom adjacent to said trigger, said means being operable to actuate 80 said member to engage and impart valve opening movements to the valve stems.

4. A spray gun having a body with a spray-head at one end, and a shank projecting from its other end, control-valve stems 85 mounted in the body and operable to control the discharge of air and material from the spray-head, a trigger pivotally mounted within the body in advance of the shank and in engaging relation to said valve 90 stems, a body support in engagement with said shank and having a chamber therein, and means disposed within the chamber and having a reciprocally movable part projecting therefrom in trigger engaging position 95 and operable to actuate the trigger to impart valve opening movements to the stems.

5. A spray gun having a body with a spray-head at one end and a shank projecting from its opposite end, control-valve 100 stems mounted in the body and operable to control the discharge of air and material from the spray-head, a trigger mounted in the body in advance of its shank and operable to impart valve opening movements to 105 said stems, a support for the body having at its upper end an apertured boss for receiving the body shank and having a cylindrical chamber, the axis of which is transverse to the body, and means mounted in the chamber 110 and having a part reciprocally movable axially thereof and projecting from the inner end of the chamber in trigger engaging position, said means being operable to move said part to engage and actuate said 115 trigger to impart valve opening movements to said stems.

6. A spray-gun having control valves for the discharge therefrom of air and the material being sprayed, and means operable to 120 open said valves including a trigger member and a reciprocally movable member for actuating the trigger member.

7. A spray-gun having control valves for the discharge of air and liquid therefrom, 125 a valve actuating member movable to act on the valves to effect an opening thereof, and electrically operated means having a

plunger part for engaging and actuating the valve opening movements of said member.

8. A spray-head having separate discharge orifices for material to be sprayed and a motive agent, a separate valve for controlling the discharge from each orifice, electrically operated means having a recipro-

cally movable plunger part, and connection between each of said valves and said plunger part operable to open the valves when the means is energized.

In testimony whereof, we have hereunto signed our names to this specification.

WILLIAM F. GRADOLPH.
GODFREY MUELLER.
